(57) **CLAIM**

The ornamental design for a foot support device, as shown and described.

DESCRIPTION

This application claims priority to U.S. Application Ser. No. 11/615,515, filed Dec. 22, 2006, now pending, the disclosure of which is incorporated by reference in its entirety herein.

FIG. 1 is a perspective view of a foot support device showing our new design;

FIG. 2 is a front view thereof;

FIG. 3 is a side view thereof, as taken from the left side in FIG. 2;

FIG. 4 is a rear view thereof;

FIG. 5 is a side view thereof, as taken from the right side of FIG. 2;

FIG. 6 is an end view thereof, as taken from the top of FIG. 2; and,

FIG. 7 is an end view thereof, as taken from the bottom of FIG. 2.

The broken lines in FIG. 1 showing a foot and a leg illustrate environmental structure which forms no part of the claimed design.

It is understood that the broken lines within the surface of the claimed design indicates stitch lines which forms no part of the claimed design.

1 Claim, 3 Drawing Sheets
